US00D900846S

(12) **United States Design Patent** (10) Patent No.: **US D900,846 S**
Baker et al. (45) Date of Patent: ** Nov. 3, 2020

(54) **DISPLAY SCREEN OR PORTION THEREOF
WITH GRAPHICAL USER INTERFACE**

(71) Applicant: **Apple Inc.**, Cupertino, CA (US)

(72) Inventors: **Robert W. Baker**, Cupertino, CA (US);
Sebastian Boltz, Elmshorn (DE);
Joshua W. Decker, San Francisco, CA
(US); **Soeren Kelling**, Rellingen (DE);
Ole Lagemann, Rellingen (DE)

(73) Assignee: **Apple Inc.**, Cupertino, CA (US)

(**) Term: **15 Years**

(21) Appl. No.: **29/682,669**

(22) Filed: **Mar. 7, 2019**

Related U.S. Application Data

(63) Continuation of application No. 29/624,545, filed on Nov. 1, 2017, now Pat. No. Des. 847,841.

(51) LOC (12) Cl. **14-04**

(52) U.S. Cl.

USPC **D14/486**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with graphical user interface showing our new design.

The peripheral dashed broken lines illustrate a display screen or portion thereof, and form no part of the claimed design.
